SECONDARY ELECTRON AMPLIFIER

Erich Schwartz, Berlin-Zehlendorf, and Heinrich Strübig, Teltow, near Berlin, Germany, assignors to the firm Fernseh Aktien-Gesellschaft, Zehlendorf, near Berlin, Germany

Application February 9, 1937, Serial No 124,936
In Germany February 10, 1936

4 Claims. (Cl. 250—175)

The invention relates to amplifier tubes in which the emission of secondary electrons from anode surfaces is used for amplification. These tubes usually operate in the manner that electrons of a certain velocity liberate secondaries from an electrode. These liberated electrons impact a second secondary-emitting electrode, and these secondaries impact a third secondary-emitting electrode, and so forth.

10 In these tubes, in which the emitting electrodes should possess surfaces capable of high secondary emission, the amplification is limited by the increasing current density because of space charge. Furthermore, the life of the amplifier tube is 15 greatly decreased by too intense an electron bombardment of the secondary-emitting surfaces.

It is the object of the invention to arrange the electrodes of subsequent stages in such a manner 20 that the current density stays within reasonable limits even in the last stages, in spite of a high amplification factor. According to the invention, this is achieved by giving the emitting electrodes an area which increases from stage to stage. This arrangement also gives a decrease 25 in space charge.

The whole amplifier by secondary emission may 30 be built in a concentric arrangement. Electrodes then have the shape of plane circular rings or truncated cones of increasing diameters, instead of the usual electrodes which have the same area in all stages.

In order to decrease the space charge still more, auxiliary electrodes, for instance, grids or other 35 permeable electrodes, are incorporated, and the distances between these auxiliary electrodes and the emitting electrodes is chosen in such a manner that in spite of a large field strength in front of the emitting electrode, the primary electrons 40 still impact the secondary emitting electrode.

The drawings show embodiments of the invention.

Figure 1 shows an amplifier with secondary emission according to the invention.

45 Figures 2 and 3 show another example of a multi-stage amplifier.

Figure 4 shows an amplifier tube with secondary emission with a magnetic field according to the invention.

50 Figure 5 shows another embodiment.

In Figure 1, vacuum receptacle 15 contains the thermionic cathode 16 for emitting primary electrons which are varied in number by the control grid 17. The primaries impact the cone-shaped 55 first secondary-emitting electrode 18, and liberate

secondary electrons which leave the cone 18 substantially perpendicularly to the axis of the cone, and impact the second secondary-emitting electrode 19. The latter has the shape of a truncated cone, whereby its inside surface is impacted by electrons, so that further secondary electrons are liberated. These are accelerated in the direction of the third electrode 20, also having the shape of a truncated cone, and impact the outer wall of this electrode. The electrodes 21, 22 and 23 are similar to the electrodes 19 and 20, and fulfill the same functions. The cone 18 and the truncated cones 20 and 22, and the truncated cones 19, 21 and 23 complement each other to form two concentric cones. The cloud of secondary electrons swings in the space between these two cones, and is finally collected by the collecting anode 24. It may be seen from Figure 1 that the area of the secondary-emitting surfaces increases from stage to stage, whereby space 20 charge and stress of the emitting electrodes is lower than in any previously known arrangements. As the space charge density increases, according to a logarithmic law, it is advisable to let the area of the secondary-emitting electrodes 25 also increase, according to a logarithmic law, in order to obtain constant space charge. When using a cone shape, a circular surface for the emitting electrodes is obtained, the generating line of which is a logarithmic line.

The voltages applied to the emitting electrodes are chosen in such a manner that the gain of secondary electrons is as large as possible in every stage of the amplifier. The electrode 18 is, for instance, given a positive voltage of 450 volts with respect to the cathode; the electrode 19, 900 volts; the electrode 20, 1350 volts; the electrode 21, 1800 volts; and so on. The auxiliary electrodes 7, 8, 9, 10 and 11, if incorporated in the tube to insure drawing of the secondaries away from the emitting surface, are, for instance, given the potential of the next following emitting electrode and may be directly connected with the latter.

If the subtended angle of the cone is enlarged 45 to 180°, an arrangement is obtained in which the electrodes consist of concentric flat cylindrical rings. Such an arrangement is shown in Figures 2 and 3. The first emitting electrode 1 is given the shape of a round plate. Secondary-emitting electrodes 2, 3, 4, 5 and 6 have the shape of a flat cylindrical ring, so that the areas of the electrodes increase proportionally to the radius with increasing number of stages. The collecting anode 24 is given the shape of a cylinder.

The invention is not limited to amplification by means of secondary emission with electrostatic fields. Devices in which the paths of the secondary electrons are controlled by means of magnetic deflection fields are also within the scope of the invention. In Figure 4, the cylindrical metal receptacle 25 has welded or soldered to the middle of the bottom of it a vertical metal pin 26; a direct current source 27 is connected 10 between the end of this metal pin 26 and the upper end of the metal receptacle 25, so that a magnetic field may be formed in the receptacle and its axis, the magnetic lines of force filling out the entire interior of the receptacle in the 15 form of complete circles. It is naturally possible to substitute a coil of suitable shape for this metal receptacle, in order to decrease the direct current required in the arrangement. The metal receptacle 25 may be either directly placed into 20 a vacuum receptacle, or a vacuum receptacle 38 may be arranged in the interior of the metal vessel. In this vacuum vessel there are concentric flat cylindrical plates 29, 30 and 31 as secondary emitting electrodes, an electron source, 25 as for example a thermionic or photo-cathode 32, and the accelerating electrodes 33, 34 and 35. The combination of the magnetic field and the electrostatic field between the electrodes causes semi-circular paths of the primary electrons on 30 which they travel to the following secondary emitting electrode. As it is not possible to obtain a homogeneous magnetic field inside of the metal receptacle 25, the electron paths will have a greater radius as they come nearer to the outside 35 of the receptacle, and the width of the individual flat circular rings will be accordingly increased, in order to insure that the primary electrons of one ring impact the following secondary-emitting electrode.

40 A further embodiment is shown in Figure 5. In this case, the electrodes have a semi-circular shape, and are placed in a semi-circular vacuum vessel 36. The magnetic field is generated by a U-shaped magnet 37 in the front of the poles of which the vacuum vessel is arranged. The magnetic field has an approximately semi-circular shape within the range of the vacuum vessel, so that the electrons may have arch-shaped paths

from the innerplates to the outerplates, similar to the device shown in Figure 4.

Having thus described our invention, we claim:

1. An electron multiplier comprising a source of primary electrons, a series of secondary-emissive truncated cone-shaped electrodes of increasing mean diameter supported concentrically about a common axis with the inner surfaces of alternate truncated cone-shaped electrodes exposed to electron bombardment by electrons from the outer surfaces of electrodes intermediate said alternate electrodes, a secondary-emissive cone-shaped electrode supported at a point on said axis and responsive to electrons from said primary source for bombarding the first of said truncated cone-shaped electrodes in the series with secondary electrons, and a collector electrode for collecting electrons from the last of said truncated cone-shaped electrode in said series. 10

2. An electron multiplier comprising an envelope having therein a plurality of secondary-emissive electrodes of truncated cone shape, each of said electrodes having a mean diameter greater than that of the preceding electrode in the series, the inner surfaces of alternate ones of said electrodes being exposed to bombardment by electrons from the outer surfaces of those of said electrodes intermediate said alternate electrodes. 20

3. An electron multiplier comprising an envelope having therein a plurality of secondary-emissive electrodes of truncated cone shape, each of said electrodes having an area greater than that of the preceding electrode in the series, the inner surfaces of alternate ones of said electrodes being exposed to bombardment by electrons from the outer surfaces of those of said electrodes intermediate said alternate electrodes. 30

4. An electron multiplier comprising an envelope having therein a plurality of secondary-emissive electrodes of annular shape, each of said electrodes having an area greater than that of the preceding electrode in the series, the inner surfaces of alternate ones of said electrodes being exposed to bombardment by electrons from the outer surfaces of those of said electrodes intermediate said alternate electrodes. 40
